UNITED STATES PATENT OFFICE.

ALFRED BUCKSTAHL, OF DETROIT, MICHIGAN.

ELECTRIC FURNACE.

Application filed May 11, 1922. Serial No. 560,186.

To all whom it may concern:

Be it known that I, ALFRED BUCKSTAHL, a citizen of the United States of America, residing at Detroit, in the county of Wayne and State of Michigan, have invented certain new and useful Improvements in Electric Furnaces, of which the following is a specification, reference being had therein to the accompanying drawings.

10 This invention relates to electric furnaces suitable for the heat treatment of large objects at high temperatures.

It is the object of the invention to provide an arrangement of the resistors by 15 which changes and substitutions may readily be made without the necessity of cooling down the furnace and with the minimum removal of parts. The current practice in large furnaces heated by electric resistance 20 elements, is to arrange a series of insulating supports of refractory material projecting from the side walls of the furnace at points near the top and bottom of the side walls. Upon these supports is looped a continuous 25 ribbon of an alloy having high electric resistance in a sinuous path with the portions of the ribbons between the refractory supports substantially vertical. This continuous ribbon is made to extend from one end 30 of the furnace to the other upon the opposite side walls of the furnace and if any break occurs, it is necessary to allow the furnace to cool down so that a workman may enter the furnace and remove the entire heating 35 element. This operation requires considerable time and labor and during the period of replacement the furnace is out of use.

It has been proposed to provide resistance 40 conductors carried by refractory plates extending longitudinally through the furnace and supported by rail sections mounted in grooves in the bricking of the furnace arch and sides whereby the supports may be shifted longitudinally of the furnace. In 45 this case the resistance conductors are of continuous length throughout the longitudinal extent of the furnace and whenever it is necessary to replace a heating element, the front wall or rear wall of the furnace 50 must be removed to permit the withdrawal of the resistance elements with their supports.

Another familiar type of furnace has the 55 resistance element in the form of a heavy wire usually about a quarter of an inch square bent to form a hairpin-shaped ele-

ment of the length of the furnace inserted in the furnace walls with the element running from front to back. In replacing such elements the furnace must be cooled and the 60 length of the furnace in practice is limited to about six feet due to the bending of the units in the furnace. It is very difficult to remove burnt out units and there is considerable loss of heat due to the form of 65 connection made necessary by the hairpin-shape.

In the development of the electric furnace, it has been found desirable to localize heating temperatures to suit particular heat 70 conditions. Where the same furnace is to be used with different materials, it is desirable that the heat conditions may be made variable in various portions of the furnace. The present methods of arranging the heating 75 elements make this localized variation of temperature extremely difficult if not impossible.

It is the object of the present invention to provide a heating element or unit of the 80 metallic resistor type which may be inserted through the side walls of the furnace so that the heating units can be removed or interchanged without dismantling the furnace and without the necessity of cooling 85 down the furnace.

A further object of the invention is to provide a heating unit made of a suitable ribbon or wire designed to allow a wide 90 range of variation in heat so that by the substitution of one unit for another, variations in localized heat conditions may be readily made.

A further object of the invention is to provide a form of heating element in which the necessary length of resistance material 95 may be utilized transversely of the furnace so that the heat may be applied from overhead in a furnace relatively wider and lower than those at present in use. The necessity for the relatively greater height required in the present type to accomodate a sufficient length of resistance material will be obviated by the use of a form of resistor element 100 in which the necessary length of resistance material may be arranged transversely of the furnace instead of vertically upon the side walls.

A still further object of the invention is 110 to provide a heating unit which shall be convenient to handle and of relatively cheap construction.

I obtain these and other objects by the construction illustrated in the accompanying drawings, in which—

5 Figure 1 is an end elevation, parts being shown in section, of one form of furnace, containing a preferred embodiment of my device;

10 Fig. 2 is a fragmentary perspective view illustrating a removable resistor element;

15 Fig. 3 is a longitudinal section of the type of furnace illustrated in Fig. 1;

20 Fig. 4 is a horizontal section of a portion of another type of furnace illustrating a modified form of construction;

25 Fig. 5 is a vertical section through the same form of furnace;

30 Fig. 6 is a fragmentary perspective view showing the arrangement of the doors in the type of furnace shown in Figs. 4 and 5;

35 Fig. 7 is a fragmentary view showing a modification;

40 Fig. 8 is a perspective view of a modified form of resistor element;

45 Fig. 9 is a longitudinal section of a still further modification;

50 Fig. 10 is a transverse section through the modification illustrated in Fig. 9;

55 Fig. 11 is a fragmentary view showing a detail of construction; and

60 Fig. 12 is a fragmentary section of a modification.

In Fig. 1 there is illustrated a conventional form of furnace comprising a brick wall 1 surrounded by a metal shield 2 and having an inner lining 3 of fire brick or other suitable refractory material. At frequent intervals along the side wall of the furnace passageways 4 are provided of a size sufficient to permit the insertion and removal therethrough of resistance elements or units 5. These elements comprise side bars 6 preferably of an alloy highly resistant to heat and oxidation, as for example, an alloy of nickel and chromium, or of nickel, chromium and iron, and it should have substantially the same co-efficient of expansion as the heating means. The specific alloy forms no part of the present invention and may be varied to suit conditions. At the ends, the side bars 6 are separated by refractory members 7 longitudinally perforated for the reception of rods 8. The rods are provided with nuts 9 between which are clamped the bars 6. At the central portion of the element is a channel member 10 having end flanges 11 and side flanges 12 and 13, bolted, riveted or welded at 14 to the side bars 6. Lying within the channel member 10 is a bar of refractory material 15 having a series of partition members 16 upon its upper surface. The bars 7 have partition members 17 between which are arranged the looped end portions 18 of the resistance ribbons 19 of a suitable alloy. There are about twice as many partition members 16

as there are members 17, the members 16 separating parallel portions of adjacent ribbons, while the members 17 act to separate adjacent loops while permitting longitudinal movement of the loops due to their contraction and expansion under the influence of heat. The sinuously arranged ribbon supported by the transverse refractory elements 7 and 15 has its terminals 19' and 20 extending longitudinally beyond the end 70 of the frame of the unit 5 for a sufficient distance that when the unit is set in position within the furnace the ends of the resistor ribbon will extend outward beyond 75 the outer wall of the furnace. 80

Recessed bricks 21 will be used to fill the passageways 4 and upon the outside of the furnace, brackets 22 will support asbestos plates 23 which may be secured in place as 85 by nuts 24.

It will be seen that the resistor unit just described may be made of any convenient width and length for insertion and removal and it will also be evident that by varying the number of turns or loops of the resistance ribbons, the heating conditions may be made different for different units. It will thus be possible to remove a broken element or to substitute an element having a different resistance or a different amount of heating 90 surface without dismantling the furnace and without the necessity of waiting for the furnace to cool down. 95

In Figs. 4 to 8 inclusive, a modified form of furnace embodying the present invention has been illustrated. In this modification, the furnace is made in the form of a ring or annulus 25 containing a chamber 26 within which a carriage 27 is mounted for rotation. A central supporting shaft 28 is mounted in an upper bearing 29 and a lower bearing 30. The central portion of the shaft is screwthreaded as at 31 to receive an adjusting nut 32 by means of which a collar 33 may be raised or lowered. Carried by the collar 33 are suspension rods 34 attached at their lower ends to the supporting beams 35, the outer ends of which carry the annular carriage 27. Wheels 36 engaging a track 37 may be used as an additional supporting means for the outer end of the beams 35 if desired. The annular chamber 26 will be lined with a suitable refractory material 38 and sand seals 39 and 40 are provided at the joints between the lower edges of the rotary carriage 27 and the lower edge of the refractory lining 38. 110

Arranged transversely of the annular chamber 26 and substantially radially of the furnace are a series of resistance elements 41 which in the present instance are shown as consisting of arches. Each arch consists of a sinuous resistance conductor having the curved ends substantially in line with each other at each end of the arch, the metal 115 120 125

forming the resistance conductor being wider in its vertical dimensions than transversely. Preferably these elements will consist of castings though it will be evident that they 5 may be constructed of a flat ribbon first bent in a configuration similar to that shown in Fig. 8 and then bent to form an arch in which the transverse portions of the ribbon will be substantially parallel with their 10 greatest width in substantially vertical planes.

The alloy used for the resistance elements has sufficient strength even at high temperatures to support its own weight without injurious sagging and in cases where the width 15 of the furnace is not too great, the heating element may be constructed as shown in Fig. 8. The material may be in the form of a flat ribbon 42 having its runs substantially 20 parallel with the curved ends of the loops substantially in line to rest upon suitable supports at opposite sides of the chamber.

It will be obvious that instead of a rolled ribbon the material may be cast into a similar form if desired. With either form of resistance element, whether arched or straight, the terminal members 43 will be long enough to extend beyond the outer wall and the 25 passageways 44 will then be filled with 30 bricks 45, some of which may be perforated as indicated at 46 to permit the terminals 43 to pass through an insulating body with the minimum of open space. Asbestos plates 47 perforated at 48 for the passage of the 35 terminals 43, will cover the outer ends of the bricked-in passageways as a further insulation.

The furnace will preferably have a jacket 49 of sheet metal.

40 In Figs. 1, 2, 3, 5 and 6, the supports for the ends of the resistor elements are shown as formed by the ends of projecting portions 50 of the refractory lining of the side walls of the chamber.

45 In Fig. 7 the end of the resistor element is shown as resting within a recess 51 in the side wall, the projecting portion 50 shown in Fig. 1, being omitted with the consequent lengthening of the supporting framework 50 of a resistor member. This has the advantage of securing a greater length of resistance material and there is no projecting refractory material to screen any portion of the chamber from the heat of the resistor.

55 Another modification of the invention is illustrated in Figs. 9, 10 and 11. In the furnace shown in these figures, the removable resistance elements comprise side members 52 of a metallic alloy highly resistant to 60 heat and oxidation, the side members 52 being connected by transverse braces 53 of the same material. At intervals the side members 52 are formed with webs 54 arranged in pairs to receive therebetween 65 transverse bars 55 of a refractory material

such as alundum. As shown, these bars have perforations 56 which in the present instance are staggered, and through these perforations coiled spirals of resistance wire are threaded. In this manner a large heating 70 surface is exposed and by a proper arrangement of the connections of the terminals of the resistor elements, the electrical conditions and hence the heat conditions may be varied at the will of the operator. 75

The heating elements are shown as arranged above and below the chamber 57 so that heat may be applied from overhead or underneath to material supported upon the floor 58, which will be of an alloy 80 similar to that from which the bars 52 are made. This design is especially applicable to small furnaces though it will be evident that the form of resistor element shown in this modification may be applied equally 85 well to the type of furnace shown in Figs. 4, 5 and 6 or to the type of furnace shown in Figs. 1 and 3. It will also be evident that the double arrangement of heaters above 90 and beneath the material to be treated may be used in either of the other types of furnaces shown as well as in the type illustrated in Fig. 9.

Reference to an actual installation may serve to show the practical advantages resulting from the removability of the resistor elements in the manner herein disclosed. A circular furnace of a type similar to that shown in Fig. 5 was equipped with a resistance element of the kind now most commonly in use in which a ribbon is supported upon refractory supports projecting from the walls of the furnace. The ribbon is formed as a continuous element having its runs substantially vertical along the side walls of the furnace. A break occurred within the furnace, and in order to replace the element, it was necessary to allow the furnace to cool down to a temperature at which a workman could crawl into the furnace to disconnect the metallic ribbon from its supports. In spite of the provision of an artificial supply of air, it was possible to work within the furnace for only a short period of time so that the furnace was out of use for a period of from eight to ten days. The cost of a new resistor element was approximately two thousand eight hundred dollars. After the repair had been made, the furnace was in use only a short time until another break occurred whereupon the entire process had to be repeated at substantially the same cost, with the furnace out of commission for another period of from eight to ten days. 110 115 120 125

If this furnace had been equipped with resistor elements of any of the types shown in the present application, the break could readily have been located by applying testing instruments to the exposed terminals and a new element could have been inserted 130

4
in place of the one containing the broken ribbon, without waiting for the furnace to cool down, with a minimum of labor, with the loss of only a few minutes time and at 5 a very small cost as compared with that required under the present system.

The many advantages resulting from the movability of resistor elements in the manner described in the present specification 10 will be apparent to those skilled in the art. The possibility of replacement of an element by another element having a different arrangement of resistance material enables the operator to vary the heating conditions 15 in a furnace to suit various operations requiring different heat treatment. This is practically impossible in furnaces now in use wherein the winding consists of a continuous ribbon, the replacement of which 20 requires an excessive amount of time and expenditure of a considerable sum of money.

Another advantage of the present invention is that the heating elements are located above the material being treated where danger of accidental contact is reduced to a minimum; in the type of furnace in which the heating elements are arranged vertically along the side walls, the material being moved into and out of the furnace is likely 25 to be brought into injurious contact with the heating elements. Furthermore, with the overhead arrangement of the heating elements the furnace chamber may be made of less height and the heating elements will 30 extend entirely across the work being treated so that the heat will be more uniformly applied, than where the elements are arranged in the sides of the chamber.

Another important advantage of the present 40 invention is that the resistance elements are supported in a manner permitting freedom of expansion and contraction. In the type of furnace in which the resistance elements are made in the form of square rods 45 of hairpin-shape supported horizontally within the grooves in the side wall or upon supporting brackets, if friction occurs at any point, as the resistor is heated, instead of the element moving freely longitudinally, 50 it will warp and bow outward from its support or inward against the wall. When the element is permitted to cool down it will not resume its original shape, but when it is reheated the warping action will 55 continue until the element either comes into contact with another element to form a short circuit or the element will extend into the path of the material, or it will come into contact with the furnace wall and become fused thereto so that finally it will 60 be necessary to replace the element and this frequently requires that the element be chiselled away from the points with which it lies in contact. When it is remembered 65 that this replacement necessitates cooling

down the furnace to permit a workman to enter and that the workman must perform his labors within a confined space under bad operating conditions, the advantage of being able to remove the heating element 70 as a whole will be evident. A new element may be set in place and the operation of the furnace resumed without waiting to make repairs upon a defective element 75 which has been taken out.

Since the supporting framework is made of an alloy having substantially the same coefficient of expansion as that of the resistance alloy used for the heating ribbons or other resistor elements, the expansion of the 80 alloy of the resistors will be accompanied by almost equal expansion of the longitudinal members of the frame. There will thus be but little need for relative movement between the refractory supports and the resistor elements. The framework lengthens, 85 carrying the supports apart concurrently with the lengthening of the resistance alloy and there will be little or no buckling of the elements. Certain features of construction 90 illustrated but not claimed herein are shown and claimed in my co-pending applications Serial Numbers 560,187 and 560,188, filed May 11, 1922.

It will be obvious that many other changes 95 and modifications may be made in the practice of my invention without departing from its principles or sacrificing any of its advantages. I do not therefore wish to be limited to the specific details herein disclosed, but desire to claim the invention in any of its forms or modifications within the legitimate and valid scope of the appended claims.

I claim:

1. In an electric furnace, wherein the furnace walls have a lining of refractory material, with one of said walls having an opening for the admission of the material or articles to be subjected to furnace treatment, said furnace having another of its walls formed with a passageway of a size to permit insertion and removal bodily of a resistor unit, said furnace having a support for the resistor unit when the latter is in position for active service, and a resistor unit having a form and dimensions to be supported within the furnace and be movable through such passageway, the movement of the resistor unit to and from its service position being in directions substantially transverse to the direction of axis of such admission opening.
2. An electric furnace as in claim 1 characterized in that the resistor unit includes a metallic frame and a current-carrying conducting element insulated from each other to permit the frame to support the conductor in service position, the conductor and frame being movable to and from service position as a unit.
3. An electric furnace as in claim 1 char-

- acterized in that the resistor unit is in the form of a metallic frame carrying a plurality of spaced insulating elements, and a current-carrying conductor supported by the insulating elements to provide a unit within which the conductor is supported in service position, said frame, insulating elements and conductor being movable to and from service position as a unit.
10. 4. An electric furnace as in claim 1 characterized in that the resistor unit is in the form of a metallic frame carrying a plurality of spaced insulating elements, said elements having a plurality of individual depressions arranged successively in the direction of length of the element, and a current-carrying conductor supported within depressions of the insulating elements, whereby the conductor may be given desired flight arrangements within the unit, said frame, insulating elements and conductor being movable to and from service position as a unit.
15. 5. An electric furnace as in claim 1 characterized in that the resistor unit includes a metallic frame and a current-carrying conductor insulated from each other to permit the frame to support the conductor in service position, said metallic frame and conductor having substantially similar coefficient of expansion characteristics, said frame and conductor being movable to and from service position as a unit.
20. 6. In a furnace for heat-treatment activities, a treatment chamber for the articles or material to be treated, and means for producing the treatment temperatures within such chamber, said means including an electric circuit of the non-arc type, said circuit including a succession of individual heating units combinedly connected to complete the circuit and individually removable during periods when the material-admission opening to the chamber is closed and in a direction to cross the inner plane of a chamber wall to permit substitution of units.
25. 7. A furnace as in claim 6 characterized in that the units are arranged in series relation within the circuit.
30. 8. In an electric furnace, wherein the furnace walls having a lining of refractory material, with one of said walls having an opening for the admission of the material or articles to be subjected to furnace treatment, said furnace having a plurality of passageways each of a size to permit insertion and removal bodily of a resistor unit, and a plurality of resistor units each having a form and dimensions to be supported within the furnace and be movable through one of such passageways, the movement of a resistor unit to and from its service position being in directions substantially transverse to the direction of axis of such admission opening, said furnace having supporting
- means for the resistor units when in service position.
9. A furnace as in claim 8, characterized in that the resistor units are combinedly connected to complete a circuit of non-arc-⁷⁰ ing characteristic within the chamber.
10. A furnace as in claim 8 characterized in that the resistor units are arranged in series relation within the circuit.
11. A furnace as in claim 8 characterized in that the resistor units are combinedly connected to complete a series relation within the temperature-producing circuit, substitution of individual units permitting control of the heating characteristics of the circuit.
12. A furnace as in claim 8 characterized in that the resistor units are combinedly connected to complete the temperature-producing circuit and individually removable⁸⁵ to permit substitution of units within the circuit, the circuit connection of units being outside of the furnace walls with the circuit completed by the positioning of units in service position.
13. A furnace as in claim 6 characterized in that each heating unit is formed to produce a heating characteristic of predetermined value, the relative arrangement of the heating units within the circuit determining⁹⁵ the zonal characteristics of the temperatures of the chamber.
14. A furnace as in claim 8 characterized in that each resistor unit is of predetermined heat-producing characteristic, the relative arrangement of units determining the zonal characteristics of the temperatures of the chamber.
15. A furnace as in claim 8 characterized in that each resistor unit is of predetermined heat-producing characteristic within the circuit, the position of the passageways being such as to permit a relative arrangement of the resistor units to set up predetermined temperature characteristics within the chamber.
16. A heating element for an electric furnace comprising a supporting framework carrying transverse refractory insulating members at each end and at the central portion thereof, said insulating members being provided with partition portions for an electric resistance member carried by said insulating members, said resistance member comprising a series of substantially parallel portions separated substantially midway of their length by the partition portions of the centrally located insulating member.
17. A heating element for an electric furnace, said element having a supporting framework, said framework having refractory insulating members at each end, and an electric resistance member having a series of substantially parallel portions supported¹²⁵ at their ends upon said refractory insulat-

ing members, said electric resistance member and the side members of the supporting framework being constructed of alloys resistant to heat and oxidation and having substantially the same co-efficient of expansion.

18. A heating element for an electric furnace, said element comprising a supporting framework of an alloy highly resistant to heat and oxidation, refractory insulating members carried by said framework, and an electric resistance member comprising a strip of ribbon supported by said refractory insulating members, the framework and resistance member having substantially the same co-efficient of expansion.

19. As a means for preventing the buckling of an electric resistance member in an electric furnace, insulating supporting members carrying said resistance member, and a supporting element for said insulating members arranged substantially parallel with said electric resistance member and exposed to the heat thereof, said supporting element and said resistance member having substantially the same co-efficient of expansion.

20. As a means for producing variable heat conditions within the treatment chamber of a furnace operating under high temperature conditions, means for producing the treatment temperatures within the chamber, said means being in the form of an electric circuit of the non-arcing type, said circuit in-

cluding a plurality of resistor units each active in the completion of the circuit, each of said units having a formation to produce temperature values individual to itself when positioned in its circuit-completing position, the chamber walls being arranged to support the units in service position, and said chamber having a wall provided with openings for the passage of individual units to and from service position, the arrangement of the units relative to each other being such as to set up heating conditions within the chamber determined by the arrangement of units relative to each other within the chamber.

21. Means as in claim 20 characterized in that the units are interchangeable to produce desired temperature conditions by the position of the units within the current flow-path through the assembly of units within the chamber.

22. Means as in claim 20 characterized in that each unit includes a plurality of connected flights of a current-carrying conductor, said flights extending in direction substantially transverse to the axis of the direction of temperature variations within the chamber.

In testimony whereof I affix my signature in presence of two witnesses:

ALFRED RUCKSTAHL.
